UNITED STATES PATENT OFFICE.

RALPH WILLITS, OF INDIANAPOLIS, INDIANA.

RAILROAD-RAIL.

No. 868,743.

Specification of Letters Patent.

Patented Oct. 22, 1907.

Application filed December 3, 1906. Serial No. 346,179.

To all whom it may concern:

Be it known that I, RALPH WILLITS, a citizen of the United States, residing at Indianapolis, in the county of Marion and State of Indiana, have invented a new 5 and useful Railroad-Rail, of which the following is a specification.

My invention relates to improvements in rails for railroads; and the objects of my improvements are, 1st. To provide a rail in two sections, an upper, re- 10 movable wearing section, and a lower supporting section. 2nd. To provide a rigid joint for the lower sections. 3rd. To secure the upper to the lower section without the use of bolts, or rivets and without the ne- cessity of machine work on the upper section.

15 The accompanying drawings illustrate my invention:

Figure 1 is a side elevation of an embodiment of my invention at a point between the two lower members; Fig. 2 a section on line 2—2 of Fig. 1; Fig. 3 a section 20 on line 3—3 of Fig. 1; Fig. 4 an enlarged sectional detail on line 4—4 of Fig. 5; Fig. 5 an enlarged elevation of one of the fastening mains; Fig. 6 a sectional detail on line 6—6 of Fig. 5.

The main or wearing portion of the track is composed 25 of sections of a rolled bar 10 having a tread face on its upper side and on its under side a rib 11 with intermediate shoulders 12. The bar is of such shape as to be readily rolled, and rolled in the opposite sides of the rib 11 are grooves 13 parallel with the tread face and 30 preferably continuous.

In order to form a support for the wearing members 10 I provide a chair member which consists of a main 35 central horizontal web 14 provided on its upper face, at its sides, with comparatively short, slightly diverging flanges 15, which thus form between them a groove adapted to receive and fit the rib 11 of the tread member 10, the upper edges of the flanges 15 engaging and supporting the shoulders 12 of the tread member, while the rib 11 thereof bottoms on the medial web 14. On 40 the lower side of web 14 I provide a pair of slightly diverging flanges 16 which, at their lower ends, are turned outward to form supporting feet 17 adapted to rest upon the ties. The supporting member or chair is a single piece which is self-supporting without transverse bolts 45 or fastenings of any kind, and the spaces between the flanges 16—16 and 15—15 are sufficiently wide to permit ready rolling of the member.

In order to secure the tread member 10 in the supporting chair without the use of bolts or other similar 50 fastenings, I form, in the upper edges of the flanges 15, shallow vertical notches 18, which extend slightly below the lower line of the groove 13 of the tread member when said tread member is in position, and formed through each flange 16, immediately below

the corresponding notch 18, is an opening 19, the purpose of which will appear, the notches 18 being staggered on opposite sides of the chair member. The fastening member consists of a main body 20 provided at its upper end with an inturned finger 21 of a width less than the width of the notch 18, and of a length sufficient to extend through flange 15 and into groove 13 of the tread-forming member. At the inner end of finger 21 I provide, at one side, a short transversely extending tip 22, the length of which is less than the difference between the width of notch 18 and finger 21, and at the other side of said finger I provide a tip 23 which is somewhat longer than tip 22, the tips 22 and 23 fitting within groove 13 of the tread-forming member. At the lower end of member 20, on its inner side, I provide a boss 24 adapted to enter the opening 19, the horizontal dimension of said boss being less than the horizontal dimension of opening 19 while the vertical dimensions of these two parts are substantially the same. The upper wall 19' of opening 19 (see dotted lines in Fig. 5) is slightly inclined downwardly in the 75 direction toward that end of the fastening member at which the short projection 22 is carried, and the upper side of boss 24 is adapted to engage this wall. Formed on the inner end of boss 24, and projecting in the same direction as extension 22, is a short finger 25 which is 80 adapted to be projected behind the inner face of flange 16, while at the opposite side of boss 24, at a distance from the plane of finger 25 substantially equal to the thickness of flange 16, is a finger 26 which initially lies substantially parallel with finger 25, as indicated in 85 dotted lines in Fig. 6.

The chair members are symmetrical relative to their vertical medial plane and are rolled of any desired length and material. These members may be conveniently spliced together by the splice shown in Figs. 1 90 and 3. Said splice consists of a medial member having a U-shaped hollow rib 30 which fits closely within the space between flanges 16 of the chair, and lateral projecting flanges 31, of a length substantially equal to the length of the foot flanges 17, said foot flanges resting 95 thereon. At each side is a fish plate comprising a vertical member 32 having a slightly inturned upper edge 33, a substantially horizontal member 34 which fits upon the upper surface of the foot flange 17 and a downward and inwardly turned lower edge 35 adapted 100 to pass beneath the outer edge of the flange 31, the upper face of the inturned portion of the edge 35 being inclined vertically so that, as the fish plate is brought to position, the finger 35 and member 34 will tend to clamp flanges 17 and 31 together. Bolts 36 and nuts 105 37 are utilized to clamp the fish plates, the splice bar and the chair members together, and, in order to prevent transverse collapsing by the bolt, a tubular brace

38, through which the bolt may pass, is inserted between the vertical arms of the U shaped rib of the splice bar.

The operation is as follows: The chair members are 5 spiked or attached in any desired manner to the ties and their abutting ends are connected by the splicing structure just described. The tread members 10 are then laid in the chair members, the joints between said tread members lying between the joints in the chair members.

10 Fastening members 20 are then inserted in the following manner; The extension 23 is passed into notch 18 and groove 13 and then slid longitudinally of the rail so that it will pass behind the flange 15 until extension 22 can be also swung through notch 18 into groove 13. The 15 lower end of the fastening member is then swung downward until boss 24 enters opening 19 and finger 25 passes behind the plane of the inner face of flange 16. Thereupon the fastening member is driven to the left (in Fig. 5), the engagement of boss 24 with the inclined wall 19' 20 of opening 19 serving to place the fastening member 20 under tension and draw the tread member firmly into the chair member. When the fastening member reaches the position shown in Fig. 5, finger 26 is struck and bent to the position shown in full lines in Fig. 6 25 where its tip lies within the opening 19 so as to prevent return movement and loosening of the fastening. In order to release the tread member, a special tool may be inserted in opening 19 and finger 26 bent back to its normal position, whereupon the fastening member 30 may be readily withdrawn. The tread member is preferably symmetrical with relation to a longitudinal vertical plane so that, after it has become worn, in the usual manner on the inside, it may be readily withdrawn and reversed in the chair.

35 It will be noticed that the means for fastening the tread member in a chair is such that vibration due to the passage of trains cannot, by any possibility, loosen or affect it in any manner.

I claim as my invention:

- 40 1. In a railroad rail, the combination with a chair member having a continuous longitudinal groove in its upper face and symmetrical with relation to a longitudinal vertical plane, of a tread member having a longitudinal rib on its lower side adapted to fit the groove in a chair member, 45 said tread member being symmetrical relative to a vertical longitudinal plane, said rib of the tread member having formed therein a longitudinal groove, and a fastening member having one end adapted to enter the groove of the tread member and the other end adapted to enter the chair 50 member at a lower point.
- 50 2. In a railroad rail, the combination with a chair member having a continuous longitudinal groove in its upper face, of a tread member having a longitudinal rib on its lower side adapted to fit the groove in a chair member, 55 said rib of the tread member having formed therein a continuous longitudinal groove, and a fastening member having one end adapted to enter the groove of the tread member and the other end adapted to enter the chair member at a lower point.
- 60 3. In a railroad rail, the combination with a chair member having a continuous longitudinal groove in its upper face and symmetrical with relation to a longitudinal vertical plane, of a tread member having a longitudinal rib on its lower side adapted to fit the groove in a chair member, 65 said tread member being symmetrical relative to a vertical longitudinal plane, said rib of the tread member having formed therein a continuous longitudinal groove, and a fastening member having one end adapted to enter the groove of the tread member and the other end adapted to enter the chair 70 member at a lower point.
- 70 4. In a railroad rail, the combination with a chair mem-

ber having a longitudinal groove in its upper face, of a tread member having a rib on its lower side adapted to enter the groove in the chair member, said tread member having a longitudinal groove formed in the side of its rib and the 75 chair member having a notch in the wall of its groove, of a fastening member provided with a finger adapted to enter the notch in the chair member and the groove of the tread member, lateral extensions on said finger adapted to enter the groove of the tread member inside the wall of the 80 groove of the chair member, and means for securing the opposite end of said fastening member to the chair member.

5. In a railroad rail, the combination with a chair member having a longitudinal groove in its upper face, of a tread member having a rib on its lower side adapted to enter the groove in the chair member, said tread member having a longitudinal groove formed in the side of its rib and the chair member having a notch in the wall of its groove, of a fastening member provided with a finger 85 adapted to enter the notch in the chair member and the groove of the tread member, lateral extensions on said finger adapted to enter the groove of the tread member inside the wall of the groove of the chair member, a stud carried by the inner face of the opposite end of the fastening member and adapted to enter an opening formed in the 90 chair member, said opening having a downwardly inclined wall adapted to be engaged by said stud, a finger carried by said stud and adapted to be projected behind the inner face of a portion of the chair member, and a flexible finger carried by the fastening member and adapted to be projected 95 into the opening in the chair member to prevent removal of the fastening member.

6. A chair member for railroad rails comprising a main substantially horizontal web, upwardly extending flanges 105 extending longitudinally along the sides of said web, downwardly extending longitudinal flanges extending along the sides of said web and having openings at intervals for the reception of the lower end of the fastening member, and foot flanges at the lower edges of said downwardly extending flanges, all of said members being integral and the said pairs of flanges being sufficiently transversely separated to be producible by rolling.

7. A chair member for railroad rails comprising a main substantially horizontal web, upwardly extending flanges 115 extending longitudinally along the sides of said web, downwardly extending longitudinal flanges extending along the sides of said web, foot flanges at the lower edges of said downwardly extending flanges, all of said members being integral and the said pairs of flanges being sufficiently 120 transversely separated to be producible by rolling, vertical notches being formed in the upper edges of the upwardly projecting flanges and corresponding perforations formed through the downwardly projecting flanges.

8. A chair member for railroad rails comprising a main substantially horizontal web, upwardly extending flanges extending longitudinally along the sides of said web, downwardly extending longitudinal flanges extending along the sides of said web, foot flanges at the lower edges of said 130 downwardly extending flanges, all of said members being integral and the said pairs of flanges being sufficiently transversely separated to be producible by rolling, vertical notches being formed in the upper edges of the upwardly projecting flanges, and corresponding perforations having a downwardly inclined upper wall formed through the 135 downwardly projecting flanges.

9. A fastening for railway rail members comprising a main body having a transversely projecting finger at one end provided at its tip with lateral projections, and means at its opposite end for attachment to the rail support. 140

10. A fastening for railway rail members comprising a main body having a transversely projecting finger at one end provided at its tip with lateral projections, and having at its other end a stud projecting in the same general direction as the said finger, and lateral oppositely projecting 145 fingers lying in different planes.

11. A railroad rail comprising a chair member having a longitudinal groove in its upper face and a receiving opening at a lower point for one end of the fastening member, a tread member having a longitudinal rib adapted to fit said 150 longitudinal groove, said rib having in its sides means for

receiving one end of a fastening member, and the said fastening member having one end adapted to engage the tread member and the other end adapted to engage the chair member at a lower point, and means for preventing accidental displacement of said fastening member relative to the chair and tread.

12. A railroad rail comprising a chair member having a longitudinal groove in its upper face, a tread member having a longitudinal rib adapted to fit said longitudinal groove, said rib having in its sides longitudinal grooves, and a fastening member having one end adapted to lie in the groove of the tread member and to engage the chair member to prevent transverse displacement of the fastening member, and said fastening member also having a portion adapted to be secured to the chair member at a point below its engagement with the tread member.

13. A railroad rail comprising a chair member having a longitudinal groove in its upper face, a tread member having a longitudinal rib adapted to fit said longitudinal groove, said rib having in its sides longitudinal grooves, and a fastening member having one end adapted to lie in the groove of the tread member and to engage the chair member to prevent transverse displacement, said fastening member also having a spud adapted to enter the chair member at a lower point, a lip 25 to engage the chair member to prevent transverse displacement, and a lip 26 to engage the chair member to prevent longitudinal displacement.
